James V. Washburn,
Inventor
By Atty. George Earle Seymour

UNITED STATES PATENT OFFICE.

JAMES V. WASHBURN, OF WATERBURY, CONNECTICUT.

GARMENT-SUPPORTER.

SPECIFICATION forming part of Letters Patent No. 657,302, dated September 4, 1900.

Application filed October 26, 1898. Serial No. 694,622. (No model.)

To all whom it may concern:

Be it known that I, JAMES V. WASHBURN, of Waterbury, in the county of New Haven and State of Connecticut, have invented a new 5 Improvement in Garment-Supporters; and I do hereby declare the following, when taken in connection with the accompanying drawings and the letters of reference marked thereon, to be a full, clear, and exact description of the same, and which said drawings constitute part of this specification, and represent, in—

Figure 1, a perspective view showing one embodiment of my invention; Fig. 2, a sectional view thereof on the line *a b* of Fig. 1; 15 Fig. 3, a detached view, in inside elevation, of the back or body plate, showing the integral formation of the suspension-socket with it. Figs. 4 and 5, views in edge and front elevation, respectively, of another modification of 20 my improvement.

My invention relates to an improvement in clasps or fasteners of the type generally known as "garment-supporters," the object 25 being to produce at a low cost for manufacture a simple and effective construction, of compact, neat, and ornamental appearance.

With these ends in view my invention consists in a garment-supporter comprising a 30 skeleton socket having certain details of construction, as will be hereinafter described, and pointed out in the claim.

In carrying out my invention as shown in Figs. 1 to 3, inclusive, of the drawings my 35 improved skeleton socket comprises a central tapering spine or backbone *A* and two corresponding wings or leaves *A' A'*, each of which is formed with three slots or openings *A²*, which are slightly pitched or inclined forward 40 with respect to the axis of the spine or backbone *A*. The slots or openings may vary in number; but it is designed that they shall be large enough to permit the cords *B B*, upon which they are clasped, to protrude through them somewhat, so as to increase the force of 45 their bite. The said socket I shall herein-after refer to as the "suspension-socket," as it provides for the suspension of the garment-supporter from the cords generally employed 50 for that purpose. As shown, the said suspension-socket is formed integral with the

upper end of the back or body plate *B* of the supporter, which also comprises a front plate or finger-piece *B'* and a spring *B²*. It will be understood that the wings *A' A'*, before mentioned, are folded over and pinched firmly down upon the ends of the cords *B B*, which are thus gripped and held in place, and all the more firmly because the socket thus produced is smaller at its upper than at its lower 60 end, so that the ends of the cords will flatten or spread out in the lower end of the socket and form, as it were, a wedge, tending to prevent the cords from being pulled out of the socket. By preference the openings *A²* in 65 the wings will be formed by punching the metal from the back of the plate, so as to produce slight burs upon the front of the plate. These burs will of course augment the gripping action of the socket.

In the construction shown by Figs. 4 and 5 of the drawings my improved skeleton socket *F* is made independently of the clasp and at its lower end is formed with a flat plate *F'*, provided with a rivet *F²*, which is passed through 75 a suitable opening formed in the top of a clasp *G* and headed down upon the inner face thereof, as at *f*; but it will be observed that in all of the forms shown and described as containing my invention, the openings or 80 slots in the wings are constructed and arranged so that when the wings are folded the slots will extend on opposite sides of the central line of the fold, so as to be partly located in front and partly in the rear of the completed socket.

It is apparent from the modifications shown and described that others may also be made, and I would have it understood that I do not limit myself to the exact constructions represented, but hold myself at liberty to make such changes and alterations as fairly fall within the spirit and scope of my invention. I am aware, however, that it is old to provide the back plate or frame of a garment-supporter with a suspension-socket smaller at its 95 upper than at its lower end, and therefore do not claim such construction broadly.

Having fully described my invention, what I claim as new, and desire to secure by Letters 100 Patent, is—

A garment supporter or clasp a skeleton

suspension-socket consisting of a central tapering spine and two corresponding wings located on opposite sides of the spine, and formed with inclined openings through which
5 the material clamped within the socket protrudes so as to increase the holding effect of the socket.

In testimony whereof I have signed this specification in the presence of two subscribing witnesses.

JAMES V. WASHBURN.
